UNITED STATES PATENT OFFICE

2,570,959

VENTILATOR AND WEATHER HEAD

Clarence Divine Lutton, Baltimore, Md.

Application November 17, 1948, Serial No. 60,425

4 Claims. (Cl. 98—82)

1

This invention relates to ventilators.

An object of this invention is to provide a ventilator for mounting on an air duct or other position which is so constructed that the outside air striking the device will create a suction in the duct irrespective of the direction of the wind.

Another object of this invention is to provide a ventilator of this kind which can be used for ventilating buildings, ships, chimneys or other ducts, and which can be used as a weatherhead for a forced ventilating system.

A further object of this invention is to provide a ventilator of this kind which includes removable screens over the outer openings for keeping out birds or the like, when such protection is desired.

A further object of this invention is to provide a ventilator of this kind with a valve or damper which may be either manually adjustable or may be automatically adjustable.

With the above and other objects in view, my invention consists in the arrangement, combination and details of construction disclosed in the drawings and specification, and then more particularly pointed out in the appended claims.

Figure 1 is a horizontal section taken on the line 1—1 of Figure 2 of a ventilator constructed according to an embodiment of this invention.

Figure 2 is a sectional view taken on the line 2—2 of Figure 1.

Figure 3 is a fragmentary sectional view taken on the line 3—3 of Figure 1.

Figure 4 is a fragmentary side elevation of the device.

Figure 5 is a fragmentary sectional view taken on the line 5—5 of Figure 4.

Figure 6 is a fragmentary vertical section of a modified form of this invention.

Figure 7 is a sectional view partly broken area taken on the line 7—7 of Figure 6.

Figure 8 is a fragmentary sectional view taken on the line 8—8 of Figure 6.

Figure 9 is a bottom plan view of the valve or damper embodied in Figure 6.

Figure 10 is a fragmentary sectional view of one of the vanes embodied in each form of this invention.

Referring to the drawings and first to Figures 1 to 5 inclusive, the numeral 15 designates generally a base embodying a base plate 16 formed with a marginal depending flange 17. The base 15 has secured thereto a plurality of outer vanes generally designated as 18 which are disposed in circumferential properly spaced relation with respect to one another. Each vane 18 comprises a pair of obtusely related upright plates 19 and 20 which have extending from the outer ends thereof aligned plates 21 and 22. Plates 21 and 22 have formed on their outer edges returned flanges 23 and 24 respectively. The vanes 18 have extending from the lower ends thereof base

2

flanges 25 which are adapted to be secured to the upper side of base plate 16 by suitable fastening means, such as spot welding or the like. There is a space 26 between adjacent pairs of vanes 18 through which air or the like is adapted to freely pass.

A plurality of inner vanes generally designated as 27 are disposed inwardly from the outer vanes 18 and the inner vanes 27 confront the space 26 between the adjacent edges of the outer vanes 18. The inner vanes 27 are formed of substantially right angularly disposed plates 28 which are formed at their outer vertical edges with returned ends 29. The plates 28 at their lower ends are formed with base flanges 30 which are secured to the upper side of the plate 16 by suitable fastening means, such as spot welding or the like. The outer and inner vanes 18 and 27, respectively are also formed at the upper ends with flanges similar to flanges 25 and 30 and a top disc shaped plate 31 is secured to the upper ends of the vanes 18 and 27. A cylindrical nipple 32 is disposed within the plate 16 extending partly above and partly below plate 16. The nipple 32 is formed between the upper or lower ends thereof with an annular bead 33 which is adapted to bear against the lower side of the plate 16 to limit the upward movement of nipple 32 with respect to plate 16. The inner vanes 27 are secured to the nipple 32 by a fastening means 34 so that the nipple 32 will be firmly held with respect to the base 15 and the inner vanes 27. A disc shaped damper 35 is pivotally mounted within the nipple 32 being secured to shaft 36 which is journaled in the nipple 32. The valve member of damper 32 has secured thereto a weight 37 so that the valve member or damper will be normally held in substantially vertically disposed position under normal conditions.

A cone-shaped top member 38 is secured to the top plate 31, projecting slightly beyond the margin of plate 31 and the cone-shaped top member 38 has struck therefrom fingers 39 which are bent inwardly beneath the marginal edges of the top member 38. The base member 15 is formed with a plurality of openings 40 adjacent the inner sides of the vanes 18 so that moisture collecting within the ventilator structure may be drained therefrom.

In order to provide a means whereby birds, insects and the like will be prevented from entering the interior of the ventilator, a screen 41 is disposed across each space 26. Each screen 41 includes vertically disposed bars 42 secured in any suitable manner to the opposite vertical edge of the screen 41. The screen 41 is removably secured between adjacent vertical edges of the pairs of vanes 18 by means of clips 43 which are formed at their inner ends with reverted hooks 44 engaging the inwardly projecting

flanges 24. The clips 43 which are initially extended between strands of the wire from the screen 41 are initially hooked onto the flanges 24 and are then bent outwardly and laterally as indicated at 45. In this manner the screen 41 is firmly held across the space 26 and the mesh of screen 41 may be any suitable size to prevent birds, insects, or the like from entering the interior of the ventilator.

Referring now to Figures 6 to 10 inclusive, there is disclosed a modified form of this invention. The ventilator shown in Figures 6 to 10 inclusive, includes a bottom or base plate 15a similar to base plate 15 and also includes outer and inner vanes 18a and 27a which are similar in every detail to vanes 21. A horizontally disposed ring 46 is secured at the upper ends of the outer and inner vanes 18a and 27a and a hexagonal top plate 47 is secured by fastening means 48 to the annulus 46. The annulus 46 is formed with diametrical slots or cut outs 49, the purpose for which will be hereinafter described. A vertically adjustable valve or damper generally designated as 50 is disposed within the inner vanes 27 and comprises a circular plate 51 having secured thereto a diametrically disposed bar 52 which projects beyond the marginal edges of the plate 51. The ends of bar 52 are adapted during the assembly of the ventilator to pass through the notches or cut outs in the upper plate or ring 46. The bar 52 is formed in the center thereof with a bushing 53 having a threaded bore through which a vertically disposed valve adjusting shaft 54 is threaded.

A cylindrical nipple 55 is disposed within the base 15a and has mounted axially thereof a bushing 56 secured within the nipple 55 by radially disposed spider arms 57. The shaft 54 is journaled at its lower end in the bushing 56 and extends upwardly through the upper plate 47 to a point above the upper plate cover. A conical top member 58 is secured to the top ring or annulus 46 by fastening means 59. The top member 58 is formed to the apex thereof with a bearing bushing 60 through which the shaft 54 is journaled, and a shaft operating wheel 61 is secured to the shaft 54 above the apex of the top member 58.

The spaces 63 between the inner vanes 27a form a guide for the outer ends of the valve bar 52 so as to thereby hold the valve member 50 against rotation, while permitting the vertical movement of this valve relative of the screw shaft 54. The valve plate 51 has secured to the lower side thereof an annular gasket 64 which when the valve member 50 is completely lowered is adapted to engage the upper end of the nipple 55.

An inverted or depending conical deflector 62 is secured to the lower side of plate 47 and provides a means whereby air rising upwardly within the ventilator will be directed outwardly and laterally through the opening or space between the inner and outer vanes. The deflector 62 is used where this ventilator is a weatherhead on a mechanical ventilating system and is preferably omitted when the device is used only as a ventilator in a non-mechanical system. A mechanical system is defined as one embodying a motor operated blower. The construction shown in Figure 6 may be used to provide for egress or ingress of air or the like to a duct with which the nipple 55 is connected on mechanical systems.

It will be understood that the outer vanes 18a may have secured thereto screens similar to

screens 41 to prevent birds, insects or the like from entering the interior of the ventilator with a ventilator as hereinbefore described. A syphon action is provided for withdrawing air from a ventilating duct and this syphon action will occur irrespective of the direction of the wind.

I do not mean to confine myself to the exact details of construction herein disclosed but claim all variations falling within the purview of the appended claims.

What I claim is:

1. A ventilator comprising a centrally apertured bottom member and a top member vertically spaced therefrom, a nipple means extending through said bottom member and spaced from said top, a plurality of circumferentially disposed inner vanes extending vertically between said bottom and said top members forming inner spaces between said vanes communicating with said nipple, said inner vanes having substantially right angularly disposed side plates terminating in reversely turned outwardly oppositely disposed edges spaced from said side plates, a plurality of circumferentially disposed outer vanes connecting said bottom and said top members outwardly of said inner vanes, said outer vanes being spaced apart to form outer spaces opening therebetween said spaces being aligned with said inner vanes, said outer vanes having outwardly obtusely related angled upright plates connecting oppositely disposed aligned upright end plates comprising part of said outer vanes, said upright plates being radially disposed from said inner spaces, said substantially right angular plates and said aligned end plates forming parallel wall channels extending therebetween for communicating an adjacent said inner space with an adjacent said outer space.

2. A ventilator as defined by claim 1 having vertically disposed angular clips carried by opposed pairs of vanes with screen means extended between said vanes and secured thereto by said clips.

3. A ventilator as defined by claim 1 having a vertically adjustable damper member formed with oppositely disposed extensions extending into at least two of said inner spaces.

4. The construction of claim 1 wherein an inverted conical deflector member is secured to said top member.

CLARENCE DIVINE LUTTON.
